(57) **CLAIM**

The ornamental design for an apparatus for storing and dispensing propellant, a bullet, and a primer for a muzzleloader, as shown and described.

DESCRIPTION

FIG. 1 is a front, right, bottom perspective view of the apparatus for storing and dispensing propellant, a bullet, and a primer for a muzzleloader;

FIG. 2 is a left, side elevation view of the apparatus for storing and dispensing propellant, a bullet, and a primer for a muzzleloader;

FIG. 3 is a front elevation view of the apparatus for storing and dispensing propellant, a bullet, and a primer for a muzzleloader;

FIG. 4 is a rear elevation view of the apparatus for storing and dispensing propellant, a bullet, and a primer for a muzzleloader;

FIG. 5 is a right, side elevation view of the apparatus for storing and dispensing propellant, a bullet, and a primer for a muzzleloader;

FIG. 6 is a bottom plan view of the apparatus for storing and dispensing propellant, a bullet, and a primer for a muzzleloader;

FIG. 7 is a top plan view of the apparatus for storing and dispensing propellant, a bullet, and a primer for a muzzleloader;

FIG. 8 is a perspective view of the apparatus for storing and dispensing propellant, a bullet, and a primer for a muzzleloader in use with a muzzleloader;

FIG. 9 is a perspective view of the apparatus for storing and dispensing propellant, a bullet, and a primer for a muzzleloader in use with a muzzleloader; and,

FIG. 10 is a perspective view of the apparatus for storing and dispensing propellant, a bullet, and a primer for a muzzleloader in use with a muzzleloader.

The dash-dash lines shown in FIGS. 1-6 and 8-10 show portions of the apparatus for storing and dispensing propellant, a bullet, and a primer for a muzzleloader that form no part of the claimed design. The dot-dash lines shown in FIGS. 8-10 are for the purpose of illustrating a muzzleloader and form no part of the claimed design.
